CLAIM

(57) I claim the ornamental design for a cosmetics container, as shown and described.

DESCRIPTION

FIG. 1 is a top perspective view of a cosmetics container showing my new design;

FIG. 2 is a left side elevation view thereof;

FIG. 3 is a right side elevation view thereof;

FIG. 4 is a rear elevation view thereof;

FIG. 5 is a front elevation view thereof;

FIG. 6 is a top plan view thereof;

FIG. 7 is a bottom plan view thereof; and,

FIG. 8 is an exploded top perspective view of the cosmetics container of FIGS. 1-7 with the cap removed.

The evenly dashed broken lines in the drawings illustrate the portions of the cosmetics container that form no part of the claim. The short dash-long dash broken lines in the drawings indicate the cap placement.
